WINDOW CONSTRUCTION

Henry R. McCleary, Detroit, Mich.

Application December 10, 1937, Serial No. 179,043

8 Claims. (Cl. 98—97)

This invention relates to windows and has for its primary object to provide for ventilation when storm sash are used in conjunction with casement windows of the type which open outwardly. The conventional storm sash is usually provided with a plurality of openings which are ordinarily covered by a pivotally mounted cover, and when ventilation is required the cover is moved to a position uncovering the openings. This is a simple matter when storm sash are used in conjunction with vertically slidable windows, but in the case of outwardly swinging casement windows it is impossible to open them, due to interference by the storm sash, to an extent whereby a person's hand may be inserted to move the cover. To overcome this difficulty the present invention provides means which functions automatically incident to opening movement of the casement window to move the cover member away from the openings in the sash.

Another object of the invention is to provide apparatus of the character above mentioned wherein the movement of the cover member is directly proportional to the movement of the casement window in order that the area of the ventilating openings may be varied at will.

With the above and other ends in view the invention is more fully disclosed with reference to the accompanying drawings, in which

Figure 1 is a horizontal section;

Fig. 2 is a fragmental elevation of a storm sash;

Fig. 3 is a vertical section taken on the plane indicated by line 3—3 of Fig. 2;

Fig. 4 is a section taken on the plane indicated by the line 4—4 of Fig. 2, but illustrating the parts in a different position;

Fig. 5 is a perspective view illustrating a slightly modified construction;

Fig. 6 is an elevation illustrating a modified cam bracket, and

Fig. 7 is a section thereof.

Like characters of reference are employed throughout the description and drawings to designate corresponding parts.

A casement window sash 1 is supported for swinging movement by a hinge 2, the direction of such swinging movement being toward a storm sash 3 which is supported in spaced relation to the sash 1. In the lower portion of the sash 3 is a plurality of ventilating openings 4 and a pivoted cover member 5 adapted to cover the openings. The cover member 5 is formed of sheet metal and is pivoted at 6 whereby its free end engages a bracket 7 when it is positioned

over the openings 4. A spring 15 has one end attached to the sash 3 and its other end connected to the cover member whereby it functions to normally hold the cover member over the openings.

Also mounted upon the pivot 6 is a rocking lever 8 having one end in engagement with a pin 9 carried by the cover member 5 and its other end in engagement with a plate 10. That is, one end of the rocking lever 8 engages beneath the pin 9 on the cover member, and its other end engages beneath the plate 10. The plate 10 is hingedly connected at 11 to a second plate 12 which is pivotally connected at 13 to a bracket 14 mounted on the sash 3. The axis of the pivot 13 is parallel to the axis of the pivot 6.

Mounted on the sash 1 is a cam-like bracket 16 which is normally disposed adjacent to the plate 10. As the sash 1 is moved from the closed position shown in Fig. 3 to the partly opened position shown in Fig. 4 the cam-like bracket 16 strikes the plate 10 and depresses the same, thereby rocking the lever 8 and causing movement of the cover member 4 from the position shown in full lines in Fig. 2 to that shown in dotted lines. As the lever rocks, the plate 12 shifts about the pivot 13 and there is no binding action between the plate 10 and the rocking lever. When the sash 1 is restored to the position shown in Fig. 3 the spring 15 restores the cover member 4 to its normal position.

It becomes apparent from the foregoing that the cover member is moved automatically incident to outward swinging movement of the sash 1, and that the extent of movement of the cover member is proportional to the extent of movement of the sash 1. Therefore, the openings may be partially or completely uncovered at the will of the operator.

In Fig. 5 there is shown a partly modified form of the invention. In this form the sash 3a has openings 4a and a cover member 5a pivoted at 6a. A rocking lever 8a is mounted on the pivot 6a with one end engaging a pin 9a on the cover member and its other end engaging the underside of a plate 10a. The plate 10a is hingedly connected at 11a to a plate 12a. The plate 12a, instead of being pivotally connected to the sash 3a as in the case of the plate 12, is rigidly connected to the sash 3a. It will be noted, however, that the plate 12a is mounted at such an angle that the axis of the hinge 11a is at an angle to a horizontal plane.

When the cover member is moved from closed to open position the lever 8 rocks to such an

extent that the angular position of the end engaging the plate 10 or 10a changes materially. There is a tendency, due to this angularity, for the plate and lever to bind. This is overcome 5 in one case by permitting the plate 10 to shift with the rocking lever, and in the case of the plate 10a by supporting the plate at a favorable angle.

In Figs. 6 and 7 there is illustrated a modified 10 cam bracket composed of two parts, the cam portion 20 and the base portion 21. The cam portion 30 is secured to the base portion by bolts 22 which extend through slots 23 in the base portion. This construction is designed to adapt the apparatus 15 above described for installation in window structures wherein the distance between the casement window and the storm sash varies.

Although specific embodiments of the invention have been illustrated and described it will 20 be understood that various changes may be made within the scope of the appended claims without departing from the spirit of the invention, and such changes are contemplated.

What I claim is:

- 25 1. In combination, a swinging window sash, a storm sash mounted in spaced relation thereto, ventilating means in said storm sash, a cover for said ventilating means pivotally mounted on said storm sash, cam means mounted on said swinging window sash, and means mounted on said cover engageable with said cam means for opening said cover when said swinging window sash is opened and closing said cover when said swinging window sash is closed.
- 30 2. In combination, a storm sash, a swinging sash movable in a direction toward said storm sash, ventilating means in said storm sash, a cover for said ventilating means pivotally mounted on said storm sash, cam means mounted on said swinging sash, and means mounted on said cover engageable with said cam means for opening said cover when said swinging sash is opened and closing said cover when said swinging sash is closed.
- 35 3. In combination, a storm sash, a swinging sash movable in a direction toward said storm sash, ventilating means in said storm sash, a cover for said ventilating means pivotally mounted on said storm sash, cam means mounted on said swinging sash, means mounted on said cover engageable with said cam means for opening said cover when said swinging sash is opened and closing said cover when said swinging sash is closed, and yieldable means acting to move said cover toward closed position.
- 40 4. In combination, an inner swinging sash, an outer sash having an opening therethrough, a movable closure member for said opening, said closure member being movable between opened

and closed positions, yieldable means acting to move said closure member from one of said positions to the other of said positions, and means operatively connecting said swinging sash and said closure member, said closure member being movable in a direction opposite to that induced by said yieldable means by and upon movement of said swinging sash.

5. In combination, a movable sash, a storm sash having a ventilating opening therein, a cover 10 member, a pivot supporting said cover for movement over said opening, a rocking lever on said pivot having one end connected to said cover member, and means at the other end of said lever adapted to be actuated incident to movement of 15 the movable sash for removing said cover from said opening.

6. In combination, a movable sash, a storm sash having a ventilating opening therein, a cover 20 member, a pivot supporting said cover for movement over said opening, a rocking lever on said pivot having one end connected to said cover member, means at the other end of said lever adapted to be actuated incident to movement of 25 the movable sash for removing said cover from said opening, said last named means comprising a hinge having one plate secured to the storm sash and its other plate engaging the lever, and a cam-like member on the movable sash adapted to engage said other plate when the movable sash 30 is moved.

7. In combination, a movable sash, a storm sash having a ventilating opening therein, a cover member, a pivot supporting said cover for movement over said opening, a rocking lever on 35 said pivot having one end connected to said cover member, means at the other end of said lever adapted to be actuated incident to movement of the movable sash for removing said cover from said opening, said last named means comprising a hinge having one plate pivotally secured to the storm sash and its other plate engaging the lever, and a cam-like member on the movable sash adapted to engage said other plate when the movable sash 40 is moved.

8. In combination, a swinging window sash, a storm sash mounted in spaced relation thereto, ventilating means in said storm sash, a cover for 45 said ventilating means pivotally mounted on said storm sash, cam means mounted on said swinging window sash, means mounted on said cover engageable with said cam means for opening said cover when said swinging window sash is opened and closing said cover when said swinging window sash is closed, and means for maintaining said 50 cover closed when said cam means is inoperative.

HENRY R. McCLEARY.
